(57) **CLAIM**

The ornamental design of a flexible receptacle, as shown and described.

DESCRIPTION

FIG. 1 is a front, right, top perspective view of a flexible receptacle, illustrating the novel design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof; and,

FIG. 8 is an alternative view of the front, right, top perspective view thereof, with the zippers opened, illustrating the novel design in detail.

The broken lines in the drawings depict unclaimed subject matter only and form no part of the claimed design.
